UNITED STATES PATENT OFFICE.

JEHU LOREE WARD, OF HUTCHINSON, KANSAS.

GEARING.

1,401,659.

Specification of Letters Patent. Patented Dec. 27, 1921.

Application filed April 23, 1920. Serial No. 376,049.

To all whom it may concern:

Be it known that I, JEHU LOREE WARD, a citizen of the United States, and a resident of Hutchinson, in the county of Reno 5 and State of Kansas, have invented certain new and useful Improvements in Gearing, of which the following is a specification.

The present invention relates to gearing, and more particularly to an improved variable speed and reverse gearing.

The object of the invention is to provide gearing of this character which embodies the desirable features of both selective and planetary types and which is especially 15 adapted for use with that class of motor vehicles requiring only two speeds forward and a reverse.

Another object is to provide gearing of this character in which the necessity for the 20 use of brake bands, jack shaft, individual selectors is obviated.

Another object of the invention is to provide a device of this character of simple and durable construction, reliable in operation 25 and simple and inexpensive to manufacture.

Other objects and advantages reside in certain novel features of construction, combination and arrangement of parts which will be hereinafter more fully described and 30 particularly pointed out in the appended claims, reference being had to the accompanying drawings forming part of this specification, and in which:

Figure 1 is a side elevation of my improvement, the housing being shown in section and parts being broken away for the sake of illustration;

Fig. 2 is a side elevation, showing the gearing in reverse;

Fig. 3 is a transverse sectional view, taken on line 3-3 of Fig. 2;

Fig. 4 is an elevational view, the gearing being shown in low;

Fig. 5 is a transverse sectional view on 45 the line 5-5 of Fig. 4;

Fig. 6 is a vertical longitudinal sectional view on line showing the gearing in high.

Fig. 7 is a sectional view on line 7-7 of Fig. 4.

Referring to the drawings, the housing 10 is preferably constructed in two sections, 11 and 12, respectively, the meeting ends of

the sections being secured together in any suitable manner. The section 11 is provided with a bearing 13 and the section 12 55 is provided with a bearing 14.

A driven shaft 15 is provided with a universal joint 16, and the end of the driven shaft indicated at 17, is journaled in the bearing 13. This end of the shaft is provided with an axial bore 18 extending for a substantial distance of the shaft, and the extreme end of the shaft has the portion surrounding the axial bore formed to constitute a ratchet clutch member 19. A drive shaft 20 is slidably and rotatably mounted in the bearing 14. The drive shaft carries a collar 21, with which the yoke 22 of a selector or control lever operates to impart sliding movement to the shaft and to thereby control the gearing as will hereinafter appear. The inner end of the drive shaft indicated at 24, is slidably and rotatably mounted in the axial bore 18 of the driven shaft and the inner end of the drive shaft 65 carries a ratchet clutch member 25 which is fixed to the shaft and which is adapted in the extreme inner position of the drive shaft to engage the clutch member 19 of the driven shaft and thereby directly connect the drive 70 shaft to the driven shaft and transmit the motion of the drive shaft unchanged to the driven shaft.

Drive pinions, preferably a pair as indicated at 26 and 27, are secured to the drive 85 shaft. As shown in Fig. 6, these drive pinions are preferably mounted on a hub 28 and are secured to the drive shaft by a key 28'. The key 28' serves to secure the pinions 26 to the drive shaft so that they are 90 not only constrained to rotate therewith but they are also held against longitudinal displacement on the drive shaft.

A frame or carrier indicated generally at 29, is loosely mounted on the drive shaft so 95 as to be freely rotatable with respect to the drive shaft but to be held against longitudinal motion with respect to the drive shaft. Consequently, any sliding motion that it imparted to the drive shaft is partaken of 100 by the frame or carrier, whereas the rotary motion of the drive shaft is never directly communicated to the carrier. The carrier comprises a pair of spaced circular plates

30 and 31, which are provided with hubs 30' and 31', respectively. As shown in Fig. 6, the hub 31' of the right-hand plate 31 is supported directly by the drive shaft, where-
5 as the hub 30' of the left-hand plate 30 is supported on the clutch member 25. The inner faces of the plates 30 and 31 abut against the outer faces of the drive pinions 26 and 27, respectively, so that the carrier
10 embraces the drive pinions. Spacing elements 33 are provided to maintain the plates in spaced relation. A plurality of short shafts 34 are extended between the plates and have their ends journaled therein.
15 A plurality of sets of gearing are ar- ranged upon the carrier. These sets of gear- ing include a reverse gearing and in the pre- ferred form of my invention only one other set—low speed gearing—but it is to be un-
20 derstood that additional sets of gearing to provide for additional variations in speed may be included, if desired. As seen in Fig. 3, the reverse gearing comprises a pinion 35, in mesh with the drive pinion 26 and
25 a second pinion 36 which is in mesh with the pinion 35 and which may be meshed or en- gaged with an internal gear to be herein- after fully described. The low speed gear-
30 ing as seen especially in Fig. 5 comprises a single pinion 37 which is in mesh with the drive pinion 27 and which may be meshed or engaged with the internal gear to be here- inafter fully described. Each of the pinions 35, 36 and 37 are mounted upon one of the
35 shafts 34, which are positioned to corre- spond with the arrangement of the pinions and these pinions are further provided with a hub 38, which extends to the opposite plate and thereby to maintain the respective
40 pinion against displacement from mesh with its respective drive pinion.
An internal gear 39 is preferably inte- grally formed on the housing but it may if desired be separated and be secured to the
45 housing by any suitable means. The inter- nal gear is adapted to engage or mesh with either the pinion 36 or the pinion 37 or to be out of mesh with both of these pinions. Means are provided for communicating or
50 transmitting motion of the carrier to the driven shaft. This means preferably com- prises a sleeve 40 secured to the plate 30, preferably by being formed integral there- with. The sleeve 40 is provided with a plu-
55 rality of longitudinally extending slots, preferably four in number, which consti- tute key-ways 41 and which receive keys 42 rigidly formed on the driven shaft 15. By this arrangement the carrier is free to
60 move longitudinally of the drive shaft but any rotary movement of the carrier is im- parted to the driven shaft.
In operation it will be seen that the gear-
65 ing is controlled by the lever or selector 23 which imparts a sliding motion to the drive

shaft 20. In the position of the parts shown in Fig. 1, the driven shaft is disconnected from the drive shaft and no motion of the drive shaft would be communicated to the driven shaft. If it is desired to communi-
70 cate motion to the driven shaft the lever 23 would be shifted to slide the pinion 37 into engagement with the internal gear 39. As shown in Figs. 4 and 5, the motion would be imparted to the drive pinion 27
75 and from this pinion to the pinion 37 which, being in mesh with the internal gear 39, would necessarily roll on this in- ternal gear, thus rotating the frame or carrier. The reduced motion of the frame 80 or carrier will be transmitted to the drive shaft through the sleeve 40 and key 42. When it is desired to shift the gear into high, the controlling lever is actuated to slide the drive shaft 20 farther to the left
85 until the clutch member 25 fixed to the drive shaft engages the clutch member 19 on the driven shaft. In this position the drive shaft is directly connected to the driven shaft, and the motion of the drive shaft is
90 communicated unchanged to the driven shaft. At this time both pinions 36 and 37 are out of engagement or mesh with the in- ternal gear 39, as shown in Fig. 6. If it is
95 desired to reverse the gearing the control-
ing lever 23 is actuated to slide the drive shaft 20 until the pinion 36 is engaged with the internal gear, as seen in Figs. 2 and 3. In this arrangement motion of the drive
100 pinion 26 is communicated to the pinion 35
which in turn communicates its motion to the pinion 36. The pinion 36 being in mesh with the internal gear 39 rolls on the in- ternal gear 39 and carries with it the frame or carrier, the rotation of which is however
105 reversed with respect to the motion of the drive shaft. This motion of the carrier is transmitted by the sleeve and key to the driven shaft. The neutral position is pref-
110 erably as seen in Fig. 1.

I claim:

1. In a device of the character described, a driven shaft having an axial bore in one end, said driven shaft having its extreme end portion surrounding said axial bore
115 formed to constitute a clutch member, a drive shaft having one end slidably and ro- tatably mounted in the axial bore of said driven shaft, a clutch member carried by said drive shaft and engageable with the clutch member of the driven shaft to directly connect the drive shaft and the driven shaft and communicate the motion of the drive shaft unchanged to the driven shaft, a car-
120 rier loosely mounted upon said drive shaft, a plurality of sets of gears arranged upon said carrier and driven from said drive shaft, a stationary internal gear with which the sets of gears are adapted to be selectively engaged to constrain the carrier to rotation, 125
130

a key carried by the driven shaft and a sleeve secured to the carrier and having a keyway slidably receiving said key to communicate the motion of the carrier to the driven shaft, all as and for the purposes set forth.

2. In a device of the character described, a driven shaft having an axial bore in one end, said driven shaft having its extreme 10 end portion surrounding said axial bore formed to constitute a clutch member, a drive shaft having one end slidably and rotatably mounted in the axial bore of said driven shaft, a clutch member carried by 15 said drive shaft and engageable with the clutch member of the driven shaft to directly connect the drive shaft and the driven shaft and communicate the motion of the drive shaft unchanged to the driven shaft, 20 a carrier loosely mounted upon said drive shaft, a plurality of sets of gears arranged upon said carrier and driven from said drive shaft, a stationary internal gear with which the sets of gears are adapted to be 25 selectively engaged to constrain the carrier to rotation, and means for communicating the motion of the carrier to the driven shaft, all as and for the purposes set forth.

3. In a device of the character described, 30 a driven shaft having an axial bore in one end, said driven shaft having its extreme end portion surrounding said axial bore formed to constitute a clutch member, a drive shaft having one end slidably and rotatably mounted in the axial bore of said driven shaft, a clutch member carried by 35 said drive shaft and engageable with the clutch member of the driven shaft to directly connect the drive shaft and the driven shaft and communicate the motion of the drive 40 shaft unchanged to the driven shaft, a carrier loosely mounted upon said drive shaft and constrained to longitudinal movement therewith, a plurality of sets of gears arranged upon said carrier, a drive pinion 45 for each of said sets of gears fixed to said drive shaft, a stationary internal gear with which the sets of gears are adapted to be selectively engaged to constrain the carrier 50 to rotation, and means for communicating the motion of the carrier to the driven shaft, all as and for the purposes set forth.

4. In a variable speed and reverse gearing, a drive shaft, a driven shaft, means for 55 directly connecting the drive shaft and the driven shaft to communicate the motion of the drive shaft unchanged to the driven shaft, a carrier loosely mounted upon said drive shaft, a plurality of sets of gears arranged upon said carrier and driven from 60 the drive shaft, said sets of gears including a set of reverse gearing, a stationary internal gear with which the sets of gears are adapted to be selectively engaged to constrain the 65 carrier to rotation, and means for commu-

nicating the motion of the carrier to the driven shaft, all as and for the purposes set forth.

5. In a device of the character described, a drive shaft, a driven shaft, drive pinions 70 carried by said drive shaft, a carrier loosely mounted on said drive shaft with respect to rotative movement thereof and constrained against longitudinal movement with respect to said drive shaft, said carrier consisting of a pair of spaced circular plates, a plurality of short shafts extending between and having their ends journaled in said plates, a low speed pinion mounted on one of said short shafts and engaged with one 80 of said drive pinions, a reverse gearing including a pinion mounted on one of said shafts and engaged with the other of said drive pinions, and a second pinion in mesh with said last-named pinion, and an internal 85 gear with which the low speed pinion and the second named pinion of the reverse gearing are adapted to be selectively engaged to constrain the carrier to rotation, all as and for the purposes set forth. 90

6. In a device of the character described, a drive shaft slidably mounted, a driven shaft, a carrier loosely mounted on said drive shaft, a plurality of sets of gears arranged upon said carrier and driven from 95 the drive shaft, a stationary internal gear with which the sets of gears are adapted to be selectively engaged in the different positions of the drive shaft, and means for imparting sliding movement to said drive 100 shaft, a key carried by the driven shaft and a sleeve secured to the carrier and having a key-way slidably receiving said key to communicate the motion of the carrier to the driven shaft, all as and for the purposes set 105 forth.

7. In a device of the character described, a stationary housing, a driven shaft rotatably journaled in the housing and having an axial bore in one end, a drive shaft slidably and rotatably journaled in said housing and having its inner end slidably and rotatably mounted in the axial bore of said driven shaft, a carrier loosely mounted upon said drive shaft, a plurality of sets of gears arranged upon said carrier and driven from 110 said drive shaft, a stationary internal gear with which the sets of gears are adapted to be selectively engaged to constrain the carrier to rotation, a key carried by the driven 115 shaft and a sleeve secured to the carrier and having a key-way slidably receiving said key to communicate the motion of the carrier to the driven shaft, all as and for the purposes set forth. 120

8. In a device of the character described, a stationary housing, a driven shaft rotatably journaled in the housing and having an axial bore in one end, a drive shaft slidably and rotatably journaled in said hous- 130

- ing and having its inner end slidably and rotatably mounted in the axial bore of said driven shaft, a carrier loosely mounted upon said drive shaft, a plurality of sets of gears 5 arranged upon said carrier and driven from said drive shaft, a stationary internal gear with which the sets of gears are adapted to be selectively engaged to constrain the carrier to rotation, a key carried by the driven 10 shaft and a sleeve secured to the carrier and having a key-way slidably receiving said key to communicate the motion of the carrier to the driven shaft, all as and for the purposes set forth.
- 15 9. In a device of the character described, a stationary housing, a driven shaft rotatably journaled in the housing and having an axial bore in one end, a drive shaft slidably and rotatably journaled in said housing 20 and having its inner end slidably and rotatably mounted in the axial bore of said driven shaft, a carrier loosely mounted upon said drive shaft, a plurality of sets of gears arranged upon said carrier and driven from 25 said drive shaft, a stationary internal gear with which the sets of gears are adapted to be selectively engaged to constrain the carrier to rotation, a key carried by the driven shaft and a sleeve secured to the carrier and 30 having a keyway slidably receiving said key to communicate the motion of the carrier to the driven shaft, all as and for the purposes set forth.
10. In a device of the character described, 35 a drive shaft, a driven shaft, a carrier loosely mounted upon said drive shaft with respect to rotary motion of the shaft and held against longitudinal motion with respect thereto, a plurality of sets of gears arranged 40 upon said carrier and driven from the drive shaft, a stationary internal gear with which the sets of gears are adapted to be selectively engaged to constrain the carrier to rotation, and means for transmitting the 45 motion of the carrier to the driven shaft comprising a sleeve secured to said carrier and provided with key-ways, and keys received in said key-ways and carried upon the driven shaft, all as and for the purposes 50 set forth.
11. In a device of the character described, 55 a drive shaft mounted for sliding movement, a driven shaft, a carrier loosely mounted on said drive shaft with respect to the rotation thereof and held against longitudinal motion with respect to said drive shaft, a plurality of sets of gears arranged upon said carrier and driven from said drive shaft, a stationary internal gear 60 with which the sets of gears are adapted to be selectively engaged to the different positions of the drive shaft, means for directly connecting the drive shaft to the driven shaft, means for transmitting motion to the 65 carrier to the driven shaft, and means for

imparting sliding movement to the drive shaft.

12. In a device of the character described, a drive shaft, a driven shaft, a carrier loosely mounted upon said drive shaft with respect to rotary motion of the shaft and held against longitudinal motion with respect thereto, a plurality of sets of gears arranged upon said carrier and driven from the drive shaft, and a stationary internal gear 75 with which the sets of gears are adapted to be selectively engaged to constrain the carrier to rotation.

13. In a device of the character described, a drive shaft, a driven shaft, a carrier 80 loosely mounted upon said drive shaft with respect to rotary motion of the shaft and held against longitudinal motion with respect thereto, a plurality of sets of gears arranged upon said carrier and driven from 85 the drive shaft, a stationary internal gear with which the sets of gears are adapted to be selectively engaged to constrain the carrier to rotation, and means for transmitting the motion of the carrier to the driven 90 shaft.

14. In a device of the character described, a drive shaft mounted for sliding movement, a driven shaft, a carrier loosely mounted on said drive shaft with respect to 95 the rotation thereof and held against longitudinal motion with respect to said drive shaft, a plurality of sets of gears arranged upon said carrier and driven from said drive shaft, a stationary internal gear with which 100 the sets of gears are adapted to be selectively engaged to the different positions of the drive shaft, means for transmitting motion from the carrier to the driven shaft, and means for imparting sliding movement to 105 the drive shaft.

15. In a device of the character described, a drive shaft, a driven shaft, a carrier, a gear arranged upon the carrier and driven from the drive shaft, an internal gear with 110 which said gear may be engaged, said internal gear and said first mentioned gear being relatively movable and adapted to be selectively engaged and disengaged, means for engaging and disengaging said internal 115 gear and said first mentioned gear, and means for transmitting the motion of the carrier to the driven shaft.

16. In a device of the character described, a drive shaft mounted for sliding movement, a driven shaft, a carrier loosely mounted upon said drive shaft, a gear arranged upon said carrier and driven from the drive shaft, an internal gear with which 120 said gear may be engaged, and means for 125 imparting sliding movement to the drive shaft, and means for transmitting the motion of the carrier to the driven shaft.

17. A drive shaft, a driven shaft, means for directly connecting the drive shaft to the 130

driven shaft to communicate the motion of the drive shaft unchanged to the driven shaft, a carrier loosely mounted on said drive shaft with respect to the rotation thereof and held against longitudinal motion with respect to said shaft, a gear arranged upon said carrier and driven from

said drive shaft, a stationary internal gear with which said last-mentioned gear may be engaged to constrain the carrier to rotation, and means for transmitting the motion of the carrier to the driven shaft. 10

JEHU LOREE WARD.
